H. JOHNS

SPARK PLUG

Filed Nov. 2, 1920

Inventor

Hugh Johns,

By B. M. Whalen

Attorney

UNITED STATES PATENT OFFICE.

HUGH JOHNS, OF WELLINGTON, OHIO.

SPARK PLUG.

Application filed November 2, 1920. Serial No. 421,244.

To all whom it may concern:

Be it known that I, HUGH JOHNS, a citizen of the United States, residing at Wellington, in the county of Lorain and State of 5 Ohio, have invented certain new and useful Improvements in Spark Plugs, of which the following is a specification.

My invention relates to improvements in spark plugs.

10 An important object of the invention is to provide a spark plug having electrodes so constructed or shaped, that the oil will not remain near the firing point, but draw back or drip away from the same, so that 15 carbon will not be deposited at the firing point, causing the usual short circuit, such electrodes providing a firing surface of sufficient area, to prevent the electrodes being burned at the firing point, whereby the 20 spark gap would be widened.

A further object of the invention is to provide a device of the above mentioned character, which is formed of few and simple parts, and which may be manufactured 25 cheaply.

A further object of the invention is to provide a spark plug with electrodes having a knife edge, allowing the electrodes to reach a sufficiently high degree of heat, to 30 burn the carbon deposits therefrom.

Other objects and advantages of the invention will be apparent during the course of the following description.

In the accompanying drawings forming a 35 part of this specification, and in which like numerals are employed to designate like parts throughout the same,

Figure 1 is a side elevation of a spark plug embodying my invention,

40 Figure 2 is a side elevation of the electrodes included in the same.

Figure 3 is a horizontal section taken on line 3—3 of Figure 1.

Figure 4 is a side elevation of a spark 45 plug embodying a slightly different form of my invention, and,

Figure 5 is a side elevation of an electrode included in the second form of spark plug.

50 In the drawings, wherein for the purpose of illustration are shown preferred embodiments of my invention, the numeral 10 designates the metallic body portion or casing of a spark plug, Figures 1 and 4, having a 55 reduced tubular screw-threaded portion 11, to engage within the usual screw-threaded

opening in the engine cylinder. The casing 10 receives the usual insulator 12, held therein by a gland or ring nut 13.

The numeral 14 designates an inner electrode, preferably circular throughout its upper portion, and held within the insulator 12. The upper end of the electrode 14 may be screw-threaded, at 15, to receive the usual binding nut 16. At its lower end, the electrode 14 has its opposite sides flattened, providing an arrow-head 17, having faces 18, which converge outwardly forming knife edges 19, as shown. The edges 19 converge upwardly above the points 20, and converge 70 downwardly below these points, as shown. This construction is common to Figures 1 and 4. The arrow-head 17 also has its lower tapered portion 21 converging upon the faces 18, whereby the knife edge continues 75 about the lower end of the arrow-head.

In Figures 1 and 2 the numeral 22 designates a coacting electrode, secured to the metallic tubular extension 11, and hence insulated from the electrode 14. The electrode 22 carries a head 23, having opposite faces 24, converging toward their edges, to form knife edges 25, extending about the point of the head 23. The head 23 is longitudinally curved and its upper portion diverges 85 upwardly from the arrow-head 17 and its lower portion diverges downwardly from the lower portion of the arrow-head. There is an intermediate portion 26, forming with the adjacent portion of the arrow-head, a 90 sparking surface of substantial area, for instance substantially one-eighth of an inch, such area being indicated by the transverse dotted lines 27.

In Figures 4 and 5 an electrode 28 is provided, extending straight in a downward direction, and having an angular upwardly extending head 29, which is flattened and provided with knife edges 30. The lower portion of the head 29 converges downwardly 100 from the lower portion of the arrow-head 17.

In use, by virtue of the shape of the arrow-head 17, and the angular arrangement of the coacting electrode, any oil tending to 105 accumulate at the sparking point or gap, will drain away from the same, which action is aided by the knife edges. These knife edges also heat to a sufficiently high temperature, whereby any carbon accumulating 110 at or near the sparking point will be burned off. The electrodes provide a sparking point

or space of sufficient area to prevent the electrodes being burned, with the result that the spark gap is widened.

It is to be understood that the forms of my invention herewith shown and described are to be taken as preferred examples of the same, and that various changes in the shape, size, and arrangement of parts may be resorted to without departing from the spirit of my invention, or the scope of the subjoined claim.

Having thus described my invention, I claim:

A spark plug of the character described, comprising a metallic body portion, an insulator carried thereby, an electrode carried by the insulator and having an arrow-head,

said arrow-head having longitudinal knife edges, said knife edges converging upwardly above points spaced from the lower end of the arrow-head and converging downwardly below such points, and a coacting electrode carried by the metallic body portion, the second named electrode having a head provided with a longitudinal knife edge, such knife edge having its lower portion diverging downwardly with relation to the arrow-head, said knife edges having opposed sparking spaces of substantial area arranged above the downwardly diverging portions of the knife edges.

In testimony whereof I affix my signature.

HUGH JOHNS.
